R. M. Lacey

UNITED STATES PATENT OFFICE.

JOHN CRIDER, OF CONCORDIA, KANSAS.

SHELF-BRACKET.

SPECIFICATION forming part of Letters Patent No. 427,462, dated May 6, 1890.

Application filed September 27, 1889. Serial No. 325,270. (No model.)

To all whom it may concern:

Be it known that I, JOHN CRIDER, a citizen of the United States, residing at Concordia, in the county of Cloud and State of Kansas, 5 have invented certain new and useful Improvements in Shelf-Brackets; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to brackets and fixtures for the same.

The object of the invention is the construction of a wall-strip of peculiar conformation at the end of the slot in which the adjusting or tightening bolt works, and a corresponding 20 peculiar formation of the head of the said bolt, whereby it can be readily removed and inserted through a narrow cross-slot in the said strip.

A further object of the invention is the production of a single means whereby the bracket 25 can be quickly adjusted up or down, as required, within certain limits, and which when adjusted and tightened or fastened will be as firm as if cast with the strip.

30 The improvement consists of the novel features which will be hereinafter more fully described and claimed, and which are shown in the annexed drawings, in which—

Figure 1 is a perspective view of my invention. Fig. 2 is a cross-section on the line xx of Fig. 1. Fig. 3 is a cross-section on the line yy of Fig. 1. Fig. 4 is a perspective view of the rear end of the bracket. Fig. 5 is a vertical section of the upper end of the strip on the line zz of Fig. 1, showing the manner of removing the tightening or fastening bolt by dotted lines.

The wall-strip A, of suitable length, has a vertical slot a between its edges, a cross-slot 45 b at the end of slot a , and teeth C on each side of said slot a . The rear side of the strip A is provided with vertical recesses d on each side of the slot a to give clearance for the head of the fastening-bolt E.

The bracket F is of ordinary construction, 50 except that it is provided with a lug f at its lower end, which enters slot a and guides and steadies the bracket in its movements, and with an opening f' and teeth f^2 , contiguous to the said opening, corresponding with the teeth 55 C on the strip A, with which they engage to prevent the bracket slipping. The shank or stem of the bolt passes through opening f' in the bracket and is provided with the thumb-nut G . To adjust the bracket up or down, 60 loosen the thumb-nut G sufficient to permit the disengagement of the teeth f^2 from the teeth C . The bracket can now be moved to the required position, and is fastened by retightening the thumb-nut G . 65

The inner corner m of that portion of the strip A bordering on slot a is beveled, and the corners of the bolt-head are correspondingly beveled, so that the fastening-bolt can be tipped and its head readily inserted or removed through the slot a , as shown by dotted lines in Fig. 5. When the strip is of considerable length, the slot a is interrupted or extends part way of the strip, having the solid portions N , which receive the screws or nails 75 that fasten the strip to the wall.

What I do claim as my invention, and desire to secure by Letters Patent, is—

1. The combination, with the wall-strip having slot a and teeth C on each side of the said slot a , and having recess d on its inner side, of the bracket having teeth f^2 and a bolt-opening f' , and the fastening-bolt passing through opening f' and slot a and having its head inserted and traveling in the said recess d , substantially as described. 80

2. The combination, with the wall-strip having slot a , recess d , and teeth on each side of the said slot, of the bracket having opening f' , teeth f^2 , contiguous to said opening f' , 90 and the fastening-bolt inserted through slot a and opening f' and having its head traveling in recess d , substantially as set forth.

3. The combination, with the wall-strip having slot a , recess d , and teeth on each side of the slot, of the bracket having opening f' , teeth f^2 , contiguous to said opening, and lug f , the latter traveling in slot a , and the fast- 95

ening-bolt inserted through opening *f'* and slot *a* and having its head traveling in said recess *d*, substantially as described.

4. The combination, with the wall-strip having slot *a*, cross-slot *b*, recesses *d*, and beveled corners *m*, of the bracket and the fastening-bolt having the corners of its head correspondingly beveled, substantially as and for the purpose set forth.

In testimony whereof I affix my signature in presence of two witnesses.

JOHN CRIDER.
